Andrew O'Neilie.

UNITED STATES PATENT OFFICE.

ROBERT D. SIMPSON, OF NEW HAVEN, CONNECTICUT.

DESIGN FOR A PEN-HOLDER.

SPECIFICATION forming part of Design No. 12,303, dated June 7, 1881.

Application filed November 26, 1880. Term of patent 3½ years.

To all whom it may concern:

Be it known that I, ROBERT D. SIMPSON, a citizen of the United States, residing at New Haven, in the State of Connecticut, have invented a Design for Pen-Holders, of which the following is a specification.

This design consists in a new, useful, and original shape or configuration of a pen-holder, and it relates more particularly to that portion of the holder which is grasped between the fingers and thumb, which I will term the "grasping portion."

Figure 1 of the accompanying drawings is a side view of a pen-holder, illustrating said design; and Fig. 2 represents a cross-section of said holder through its widest part.

The respective extremities of the pen-holder are of a customary form. Between these is a relatively broad grasping portion, P K, which is concavo-convex in cross-section, as shown by Fig. 2, with convex indentations I I, Fig. 1, in its otherwise parallel longitudinal edges. The offsets which connect the nib-receiving end of the holder with said grasping portion form concave curves, and those which connect the other end of the holder with said grasping portion are beveled, and the convex side

or back P of said grasping portion is furnished with a picture, as shown in Fig. 1; but the character of this picture may be varied, or it may be omitted without materially changing my design.

I have described my design as applied to a pen-holder; but it may be applied to the holder or handle of a pencil or marking-brush with like effect.

Having thus described my said design, I claim—

1. The shape or configuration of a pen-holder, consisting of extremities of customary form united by a relatively broad grasping portion, which is concavo-convex in cross-section, substantially as shown.

2. The shape or configuration of the concavo-convex grasping portion P K, having curved indentations I I in its longitudinal edges, substantially as shown and described.

In testimony whereof I affix my signature in presence of two witnesses.

ROBERT D. SIMPSON.

Witnesses:—

ANDREW O'NEILL,
HORACE M. SANFORD.
